OTHER PUBLICATIONS

Pictures of Schlage Lock, by Schlage, 1 color sheet of photographs, disclosed unknown but prior to filing date of present application.

Primary Examiner — Mark A Goodwin

(74) Attorney, Agent, or Firm — Banner & Witcoff, Ltd.

(57)

CLAIM

The ornamental design for a lock, as shown and described.

DESCRIPTION

FIG. 1 is a front perspective view of a lock showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines depicting the remainder of the lock show features that form no part of the claimed design.

1 Claim, 6 Drawing Sheets
